UNITED STATES PATENT OFFICE.

J. FREDERICK APPELL, OF CHICAGO, ILLINOIS.

SHIRT.

SPECIFICATION forming part of Letters Patent No. 224,265, dated February 10, 1880.

Application filed November 21, 1879.

To all whom it may concern:

Be it known that I, J. FREDERICK APPELL, of Chicago, in the county of Cook and State of Illinois, have invented certain new and useful Improvements in Shirts; and I do hereby declare that the following is a full, clear, and exact description thereof, reference being had to the accompanying drawings, and to the letters of reference marked thereon, which form a part of this specification.

This invention relates to a novel mode of securing a three-ply bosom in a shirt, and has for its object to gradually diminish the thickness of material from the bosom-edge to the body, so as to prevent breaking of the body in use or under the iron in laundering at the edge of the bosom.

It consists in extending the several under plies unequally beyond the outer or face-linen 20 ply.

In the following description of my improvement reference is made to the accompanying drawings, which form part of this specification.

Figure 1 is an elevation of a shirt-front and 25 a portion of the body to which it attached, containing my invention. Fig. 2 is a sectional view, showing the unequally-extended under plies of the bosom; and Fig. 3 is a similar view, showing the intermediate row of stitching passed through the body and both inner 30 plies of the bosom.

A is the multifold bosom, composed of three or more plies or thicknesses, of which a is the outer or fine-linen ply, b is the middle ply, and 35 c is the innermost ply. B is the body of the shirt.

As clearly appears from the drawings, the middle ply, b, is wider than the face-ply a, and the inner ply, c, is still wider than b. It 40 is proposed that each under ply shall be about one inch wider than the outer adjacent one, giving an extension of one inch all around of the ply c beyond the face-ply a.

The several plies a b c and the body B are 45 all joined in the inner row of stitching, a'. The body and the inner plies, or either adjacent two of them, are joined in the row b', and the body and innermost ply are connected by the

stitching c'. By this construction the thickness of material at the margin of the face-ply 50 is gradually reduced toward the single body, thereby avoiding the abrupt shoulder 55 commonly found at the former point and preventing breaking of the body at the side of the bosom, either in wear of the shirt or in ironing it.

I am aware that a re-enforce for this part of the body has been provided by a separate strip applied on the inside of the shirt; but this involves the addition of two more thicknesses at 60 the bosom-margin, which is a great objection in ironing, and which only partially remedies the fault of abrupt change in thickness from the bosom-edge to the body.

I am also aware that the outer ply of the 65 bosom has been extended over the body; but this is open to still more serious objection. The starch, in this case, must be applied to extend to the outer edge of said outer ply, where the same trouble is presented that is 70 remedied an inch inward, while, by reason of the unequal thickness produced in the bosom thus inserted, a sightly appearance cannot be given thereto.

The construction herein shown meets all 75 these objections, giving a front of uniform thickness throughout the extent of the face-ply, and, whether irregularly starched or not outside this limit, requiring no special care in laundering, and always presenting a suitably 80 finished appearance.

Having thus described my invention, I claim—

In a three or more ply bosomed shirt, the under plies, b c, of the bosom A, unequally extended beyond the outer ply, a, and beneath the body B, substantially as described, and for the purposes specified.

In testimony that I claim the foregoing as my invention I affix my signature in presence 90 of two witnesses.

J. FREDERICK APPELL.
